UNITED STATES PATENT OFFICE.

FRANK C. ESSEX AND JOE E. MAXSON, OF PIPHER, OKLAHOMA, ASSIGNEES OF ONE-
THIRD TO D. S. McNEIL, OF PIPHER, OKLAHOMA.

SECTIONAL MOLD LINER FOR TYPE-SETTING MACHINES.

Application filed February 16, 1926. Serial No. 88,618.

This invention relates to accessories for use in connection with type setting machines and has for its object the provision of a novel sectional liner adapted to be engaged 5 within the mold of a type setting machine whereby a casting of any desired length may be formed without it being necessary for the printer to keep on hand a wide variety of sizes of liners as is necessary under the ordinary system.

It is known that in all linotype or inter-type composition, a liner is used in the mold for the different sizes or points of type and length of line. It is also well known that 10 the pica is the unit of all type measurement and is twelve point in thickness. Nearly all type setting machines are constructed with a thirty pica mold into which is inserted a liner to give the desired length, and a different or separate liner must ordinarily be used 15 for every different point or length of line. For example, newspapers are printed mostly with thirteen ems, pica, in width. It therefore follows that a thirteen em liner must 20 be used, or if not, a longer one, and in the latter instance it will be necessary for the type line or slug to be cut or sawed down to a length of thirteen ems.

An additional object is to provide a liner 25 of this character which will be simple and inexpensive in manufacture, easy to assemble and use, positive in action, a great saver of time and labor and a general improvement in the art.

With the above and other objects and advantages in view, the invention consists in 30 the details of construction, and the arrangement and combination of parts to be herein-after more fully described and claimed, and 35 illustrated in the accompanying drawings, in which:—

Figure 1 is a perspective view of a liner 40 built up in accordance with the invention.

Figure 2 is a perspective view of the main 45 or base section alone.

Figure 3 is a perspective view of one of the intermediate links or sections.

Figure 4 is a perspective view of the solid 50 end section.

Figure 5 is a perspective view of the base 55 or main section looking at the side provided with a swivel, and

Figure 6 is a perspective view showing a

different form of the invention adapted for use in connection with a slightly different 55 type of machine.

It is with the above facts in view that we have designed the present invention which has for its object the provision of a liner 60 formed of a plurality of detachably connected sections, any number of which may be placed in operative position, depending upon the desired length of line or slug.

An important object is the provision of a 65 sectional liner in which all the intermediate links or sections are interchangeable, only the two endmost ones being incapable of being interchanged, it being quite clear for obvious reasons that the two end ones must be of certain type or possess certain unchanging characteristics in order to produce the proper result.

Another object is to provide a sectional liner which may be used in connection with either the well known type of linotype machine or what is known as the intertype machine, the type of machine of course depending upon or governing the nature of the molds in connection with which the liners 75 are used.

A still further object is to provide a liner 80 in which the base or main end section may be equipped with a swivel or stop so that should the operator forget to change the ejector blade when changing the measure of 85 the liner, the blade of the ejector with the swivel will do no damage as the swivel will swing out of the way and permit the blade to pass by.

Referring more particularly to the drawings, and especially to Figures 1 to 4 inclusive, we have disclosed a liner comprising a main or base section 10, an end section 11 and a plurality of intermediate sections 12, all of the latter being similar in construction but different in size. Quite obviously, there must be quite a large number of the intermediate sections carried in stock or in hand so that the assembled liner including the two ends 10 and 11 and the intermediate 95 100 member or members 12 will have the desired length.

The base section 10 is shown as provided at one side with a slot 13 as is customary in connection with all liners for use in certain 105 types of type setting machines, such as the

linotype, while the end section and intermediate sections are not provided with any such recesses.

At one side the main section 10 is formed with a dove-tailed recess 14 extending part-way therethrough as are, also, all of the intermediate sections 12, and the latter are likewise provided at the opposite sides or edges thereof with dovetailed projections 15 of such size as to fit within the dove-tailed recesses 14 as clearly indicated in Figure 1 so that a plurality of the sections may be interengaged for building up a liner of the proper length. Obviously, when the sections are assembled as indicated they will remain in assembled relation until positively disengaged.

The only difference between the end section 11 and the intermediate sections 12 is that the former is not provided with any dovetailed recess, the end opposite the dovetailed projection 15 being smooth or solid.

We may also prefer to provide a so-called "swivel" formed as an elongated bar member 16 pivoted intermediate its ends, as shown at 17, upon the end or base section. The purpose of this feature is that in case the operator of the machine forgets to change the ejector blade in accordance with the change in the length of the liner the blade when engaging against the swivel or strip member 16 will kick the latter out of place instead of causing breakage.

In some types of machines, such as the intertype, it is customary to provide a recess at the end of the liner instead of in the side, and in Figure 6, we have illustrated a liner built up of sections constructed in substantially the same manner as above indicated except that the main or base section 18 is provided in one end with a recess 19 of the shape required for the particular type of machine. A swivel may or may not be provided, as required, though at 20 there is in-

dicated a bearing hole for the swivel pivot. 45 The same type of dove-tail recess and projection is used in connection with this form for effecting connection of the different sections.

From the foregoing description and a 50 study of the drawings, it will be apparent that we have thus provided a simply constructed device for the purpose specified and one which will not only be highly efficient but a great saving in time and labor as well 55 as enabling the keeper of a print shop to reduce the amount of material or apparatus kept on hand for printing purposes used in connection with different types of machines.

It is believed that the construction, operation and advantages will be readily apparent to one skilled in the art without further explanation.

While we have shown and described the preferred embodiment of the invention, it 65 should be understood that we reserve the right to make such changes in the form, construction and arrangement of parts as will not depart from the spirit of the invention or the scope of the subjoined claim.

Having thus described the invention, we claim:—

A liner for a type setting machine mold, comprising base and end sections and a plurality of intermediate sections of different 75 lengths, disposed between and detachably connected with the base and end sections and with one another, the connecting means consisting of dovetailed projections carried by the end section and the intermediate sections, and dovetailed recesses extending part-way through the base section and the intermediate sections.

In testimony whereof we affix our signatures.

FRANK C. ESSEX.
JOE E. MAXSON.
